Attorney.

UNITED STATES PATENT OFFICE.

GEORGE M. BERGEN-STIERHOF, OF ST. LOUIS, MISSOURI.

HYDROCARBON-BURNER.

1,304,731.

Specification of Letters Patent. Patented May 27, 1919.

Application filed August 1, 1918. Serial No. 247,745.

To all whom it may concern:

Be it known that I, GEORGE M. BERGEN-STIERHOF, a citizen of the United States, residing in the city of St. Louis and State of Missouri, have invented certain new and useful Improvements in Hydrocarbon-Burners, of which the following is a specification.

My invention relates to improvements in hydrocarbon burners and has for its object

- 10 to provide a burner of the class which may be readily applied to cook stoves, ranges, heating stoves, furnaces, and in fact, any type of coal burning stove where it is possible to install same in the fire-box thereof.
- 15 A further object of the invention, is to provide a device having top and side burners, and a generating tube surrounding the upper burners.

A further object of the invention, is to

- 20 provide means for regulating the flow of gas to one, or both, of the upper burners and means for regulating the flow of gas to both of the side burners.

A still further object of the invention, is

- 25 to provide a needle valve and Bunsen arrangement for controlling the supply of generated gas and air to the several gas distributing tubes which lead to the burners.

With the above and other objects in view,

- 30 the invention consists in certain novel features of construction, arrangement and combination of parts hereinafter described and finally pointed out in the claims hereto appended.

35 In order that those skilled in the art to which the invention appertains may know how to make and use the same, I will describe the construction illustrated, in detail, and refer by reference characters to the accompanying drawings forming a part of

- 40 this specification, in which—

Figure 1, is a plan view partly in section, of a hydrocarbon burner constructed in accordance with my invention.

45 Fig. 2, is a sectional view, taken on line X—X of Fig. 1.

Fig. 3, is a detail of the needle-valve and Bunsen or mixing tube arrangement.

In carrying out the aim of my invention,

- 50 I use two upper burners A and B comprising the lower-plates 1 and 2, and the inverted cover-like burner top 3 and 4 which are detachably secured to the lower burner plates 1 and 2, respectively, by means of the stove bolts 5. Each lower burner plate 1 and 2 is provided with an annular flange 6

to help position the upper burner plates 3 and 4 thereon on the lower burner plates 1 and 2. Each lower burner plate 1 and 2 is also provided with a gas inlet opening 7 60 and 8, respectively.

The lower burner plate 1 is secured to one end of the gas distributing pipe 9, while the other burner plate 2 is secured to one end of the gas distributing pipe 10. 65

A gas distributing chamber 11 is formed at the inner ends of the gas distributing pipes 9 and 11, as clearly shown in Fig. 2.

A valve, consisting of the valve-heads 12 and 13 is mounted on the inner end of the 70 operating stem 14 for reciprocating movement in the gas distributing chamber 11. The valve-heads 12 and 13 are adapted to seat themselves in the valve seats 15 and 16, respectively, when it is desired to shut 75 off the gas supply from one or the other of the upper burners A and B. The operating stem 14 is threaded as at 17, at its outer end, and is adapted to pass through the threaded plug 18. The extreme outer end of the 80 operating stem 14 is provided with a hand-wheel 19 for turning the operating stem 14 one way, or the other, as is manifest.

A mixing tube 20 is suitably secured, at one end, to the inner ends of the gas distributing pipes 9 and 10, in such a manner, that the gas passing through the supply pipe may be directed upwardly and into the gas distributing chamber 11 for distribution to the various burners, as clearly shown. The 90 opposite end of the mixing tube 20 is provided with a gas receiving chamber 21 which is formed between the end of the pipe 20 and the valve seating wall 22 which has a tapered orifice 23 for the reception of the needle point 24 of the screw-threaded valve stem 25. The needle valve stem is provided with the operating hand wheel 26. 95

The needle valve not only controls the flow of gas to the mixing tube 20 but is also used 100 to keep the needle valve orifice clean from carbon deposits, as is manifest.

A pair of atmospheric tubes 27 are arranged on opposite sides of the mixing tube 20 and communicate at one end, through the 105 passages 28, with the mixing tube 20 adjacent the needle valve orifice 23 so that the gas leaving the orifice may siphon air through the tubes 27 for mixture with the gas during its travel through the mixing 110 tube 20 to the distributing chamber 11.

A suitable generating pan 29 having the

channels 30 is adapted to surround each of the burners A and B as shown in Fig. 1. The generating pan is provided with a valve 31 having a three way passage, so that oil 5 may be directed from the supply pipe 32 to one or both ends of the generating pan, as desired. A valve 32' controls the flow of oil to the generating pan.

A two loop generating pipe 33 is suitably 10 supported above the channeled generating pan 29 and is adapted to surround each burner A and B so the same may be readily heated when oil is burning in the generating pan, as is manifest. A valve 34 controls the 15 flow of the oil to the looped generating pipe 33. One end of the generating pipe, designated 35, is suitably connected with the gas supply chamber 21.

It will be noted from Fig. 2, that after gas 20 has been generated in pipe 33 and the gas permitted to flow to the burners A and B, that the flame from each burner will play laterally against the generating pipe and keep the same heated for generating the gas 25 to be directed to the burners.

The device is also provided when desired with a pair of auxiliary or side burners 36 and 37. These burners are each provided with a hollow arm 38. Each hollow arm 38 30 is provided with a suitable valve 39 controlled by means of the operating stem 40. The side burners are connected to the hollow stub arms 41 in any well known manner so that they may be easily removed, or attached 35 for communication with the gas distributing chamber 11, as desired.

The operation of the device is as follows:

First a supply of oil is deposited in the channel 30 of the generating pan 29 by opening valve 31, and valve 32'. When the channel 30 is filled with oil, the valve 32' is turned off and the oil ignited. The burning oil will heat the generating pipe, as is manifest. When the generating pipe has become 45 hot the oil control valve 34 is opened permitting a supply of oil to pass through the generating pipe and become vaporized while passing therethrough. The gas thus generated is permitted to travel to the supply 50 chamber 21, as is manifest. As the needle valve 25 is opened, it will be observed, the

gas finds its way out of the orifice 23 and into the mixing tube 20, siphoning as it passes the air passages 28, a sufficient amount of air to make the desired mixture 55 of gas and air to be transmitted to the gas distributing chamber 11.

Now, if gas is to be directed to both burners A and B, the valve-heads 12 and 13 are moved, by turning the valve stem 14, to the position shown in Fig. 2. If gas is only wanted for burner A, then the valve head 13 is moved into its seat 16, thus shutting off the flow of gas to burner B, and vice-versa. If the side burners 36 and 37 are also to be 65 used the valves 39 are opened so that the gas from the distributing chamber 11 may enter one or both of the side burners, as desired.

The many advantages of the herein-described burner will readily suggest themselves to those skilled in the art to which it appertains.

What I claim is:

In a device of the class described, a burner-head, a generating pan surrounding said burner, a generating tube positioned above said generating pan in such a manner that the flame from the burner may continue to heat the generating tube after it has been initially generated, means for controlling 75 the flow of oil to the generating pan, means for controlling the flow of oil to the generating tube after it has become hot, a gas receiving chamber having connection with one end of the generating tube, a mixing tube, 80 air inlets to said tube, a needle valve for controlling the flow of gas into said mixing tube, a gas distributing chamber arranged at one end of the mixing tube, a gas distributing tube connecting said gas distributing 85 chamber with the burner, a valve arranged in said gas distributing chamber for controlling the flow of gas to the burner, an auxiliary side burner, means for connecting said burner for communication with said gas 90 distributing chamber, and a valve for controlling the flow of gas from said chamber to said auxiliary side burner.

In testimony whereof, I have hereunto signed my name to the specification.

GEORGE M. BERGEN-STIERHOF.
